INVENTOR,
Albert G. Stephens,

By Minturn & Minturn,
Attorneys.

UNITED STATES PATENT OFFICE.

ALBERT G. STEPHENS, OF INDIANAPOLIS, INDIANA.

DISPLAY-CASE CLOSURE.

Application filed July 29, 1926. Serial No. 125,805.

This invention relates to service display cases as, for example, cases having glass fronts and partitions to hold supplies of a variety of products visible to the purchaser and accessible to the vendor whereby the vendor may take quantities of the products from the case readily and deliver to the purchaser, and the invention in particular relates to the rear side construction of the case.

Heretofore cases having a number of individual compartments opening to the rear have had individual door enclosures hinged to each compartment and some type of catch was required to secure the door. Such construction required a large amount of hardware for a multiple compartment case, and as the case usually was positioned to form a narrow aisle at its back, the catches projecting from the doors interfered greatly with the actions of the attendant.

With my invention, I eliminate all hinges and catches and permit quick and easy access to any compartment either to the upper part of the compartment or directly to the floor of the compartment, and I achieve a closure not only having a very low cost of production, but one quickly assembled and as quickly removed from the rear of the compartment.

Numerous other advantages of my invention will be apparent from the following description in reference to the accompanying drawing, in which—

Fig. 1, is a rear elevation of a multiple compartment case;

Fig. 2, a fragmentary side elevation of the case;

Fig. 3, a vertical section through the lower compartments on the line 3—3 in Fig. 2;

Fig. 4, a rear elevation of a single closure unit;

Fig. 5, a vertical section through the unit on the line 5—5 in Fig. 4;

Fig. 6, a vertical section through the unit on the same line 5—5 but with both doors lowered;

Fig. 7, a horizontal section through the closure unit on the line 7—7 in Fig. 4; and

Fig. 8, a single door and its guides removed from the case.

Like characters of reference indicate like parts throughout the various views.

Referring to Figs. 7 and 8, I form a door 10 with a slot or deep rabbet 11 along each vertical edge to receive therein the door

guide 12 so that the guide 12 may be dropped back into the rabbet 11 to bring the outer edge of the guide 12 flush with or below the door edge. Referring to Fig. 4, the frame 13 has slots or rabbets 14 cut in the vertical members so that when the door 10 and the two guides 12 (Fig. 8) are placed in the frame 13, the guides 12 may be pushed from the door rabbets 11 into the frame rabbets 14, but the frame rabbets 14 are of a depth less than the width of the guides 12 whereby, when the guides 12 are fully inserted into the rabbets 14, the guides 12 still extend to within the door rabbets 11.

While the guides 12 fit loosely so as to slide freely in the door rabbets 11, the guides 12 are frictionally held within the frame rabbets 14 so that the guides 12 remain in the frame rabbets 14 until forcibly pulled therefrom. The guides 12 extend substantially the entire height within the frame 13 over which the door is to be operated. For a given frame height, the door 10 is preferably cut to a trifle less than half of the height of the entire frame opening, and a second door 15, similarly formed with the side rabbets to receive another pair of guides 16 likewise retained in rabbets in the frame 13, is employed whereby the remainder of the opening may be closed, the door 15 being more than half the height of the opening so as to project beyond the door 10 when the two doors are in either the extreme top or lower positions, Figs. 5 and 6. This second door 15, here shown as the upper door, though the relative positions may be reversed, is carried in the frame 13 so as to slide up and down closely behind the door 10, and when the door 15 is pushed to the top, and the door 10 is pushed to the bottom, the entire opening through the frame 13 is then closed, as in Figs. 1, 4, and 5.

On each side of the frame and above each guide 12 and 16, I fix a spring 17 outwardly bowed as a means of securing either or both doors 10 and 15 at the top of the frame, as in the lower compartment Fig. 2. The springs 17 are so formed as to permit the doors to slide up over them so that the springs compressively engage the doors therebetween. A slight pull downward will release either or both doors.

The doors 10 and 15 may be quickly removed from the frame 13 by simply pulling the guides 12 and 16 out of the frame rab-

bets and back into the door rabbets, and the doors lifted out. No catches are required and neither are hinges.

Referring now to Figs. 2 and 3. It is desirable in some instances to use a divider 18 so as to permit scooping the contents of the bin or compartment from under the pile to prevent damage to the contents, to prevent disturbing the forward part of the pile, and to prevent damaging the contents, and my invention is of particular advantage in such instances. The divider 18 is detachably held over the two screws 19, one on either side of the frame 13, and slopes downwardly and forwardly to rest on the supporting legs 20. Assuming the compartment to be closed, access to the compartment may be had through either door 10 or 15 as may be desired.

Dropping the door 15 as in the upper compartment, Fig. 2, will give access over the top of the divider, or leaving the door 15 in its upper closed position, the door 10 may be raised as in the lower compartment, Fig. 2, and the contents accordingly may be removed from above or below the divider 18.

I claim:

1. In a show case, a door frame having parallel rabbets cut in each of the opposite vertical sides, a lower door having a rabbet cut in each vertical edge, a door guide slid- 30 ingly entered in each of said door rabbets and frictionally engaged in said door frame rabbets, said door rabbets being of sufficient depth whereby said guides may be withdrawn from the door frame rabbets to entirely within the door rabbets, whereby the door may be removed entirely from the frame, an upper door having a rabbet cut in each vertical edge, and a second guide slid- 35 40 ily entered in each of said door rabbets and frictionally engaged in the door frame

rabbet parallel to said first door frame rabbet, said upper door rabbets being sufficiently deep to carry the said second guides entirely within the rabbets upon the door guides being withdrawn from the door frame rabbets, whereby said lower door may be removed entirely from the frame, said door frame rabbets being positioned to permit the two doors to slidably pass one over the other, and all of said guides each being appreciably longer than the height of the doors.

2. A show-case having a rear opening frame, an upper door, a lower door, an upper door guide frictionally engaged in the door frame on each side to project to within slots cut in each vertical edge of the upper door, said door slots being sufficiently deep so that the guides may be pulled into the slots to permit the door being entirely removed from the frame, a lower door, a lower door guide frictionally engaged in the door frame on each side and spaced apart from said upper door guide to project to within a slot on each vertical edge of the lower door, said lower door slots being sufficiently deep to permit said lower door guides to be pulled back therein and the door removed entirely from the frame, each of said doors thereby being vertically slidably carried in the frame, one to pass over the other, a divider board positioned in the case to have its rear upper edge near the top edges of both doors when in the lowest positions in the frame, whereby said upper door may be raised to close the opening over said divider board and said lower door raised to provide an opening under the divider board.

In testimony whereof I affix my signature.

ALBERT G. STEPHENS.
